UNITED STATES PATENT OFFICE.

WILLIAM W. McMAHAN, OF DETROIT, MICHIGAN, ASSIGNOR TO MORGAN & WRIGHT,
A CORPORATION OF MICHIGAN.

PREPARATION OF LAMPBLACK FOR USE IN COMPOUNDING RUBBER.

Application filed November 3, 1916. Serial No. 129,290.

To all whom it may concern:

Be it known that I, WILLIAM W. McMAHAN, a citizen of the United States, residing at Detroit, county of Wayne, State 5 of Michigan, have invented certain new and useful Improvements in the Preparation of Lampblack for Use in Compounding Rubber, of which the following is a full, clear, and exact description.

10 This invention relates to the preparation of lampblack for use in compounding rubber, and has for an object to prevent dispersion of the lampblack into the atmosphere during the milling operation.

15 Lampblack, while being compounded with rubber on mill rolls, permeates the atmosphere and smudges the white and other colored rubber stocks which are being milled in the same room. In order to remedy this 20 condition, the present invention provides a process for changing the physical state of the lampblack from a loose easily dispersable powder, to a compactly pressed cake or mass in which the particles are bound together 25 by molecular cohesion. In this condition the lamp black is capable of being milled with the rubber without the annoying dispersion hitherto encountered.

Apparatus for carrying out the invention 30 is shown in the accompanying drawing of which the figure is a longitudinal sectional view of a hydraulic press with a bag of lampblack therein.

In utilizing the apparatus, I take a mass 35 of lampblack 10 in the usual form of a loose powder, and preferably enclosed in an envelope, such as a paper bag 11, and place the same in the compression chamber 12 of a hydraulic press 13. The head 14 of 40 the press is then bolted down and a hydraulic pressure of about three thousand pounds is kept on the ram 15 for about one minute. The pressure is then released, the head is opened, and the compactly pressed lamp- 45 black is removed from the press in the form of a solid cake.

It is essential that the compression chamber be vented so that the air within the chamber and within the mass of lampblack 50 can escape during the pressing operation, and for this purpose I provide a plurality of vent openings 16, preferably disposed in the head 14 of the press. The envelope 11

prevents the forcing out of the lampblack through these vent openings, while at the 55 same time it is readily torn at places if a paper bag is used, and will be porous if a cloth bag is used to permit the escape of air from between the particles of the lampblack during the period the pressure is on. 60

The product is a cake of lampblack unadulterated with binders of any kind to hold the particles together. The particles are bound together, as I now believe, by their 65 own molecular cohesion, which may be explained in this manner. Lampblack, in the form of a loose powder, exhibits particles isolated from each other by air in which condition it is easily dispersed. Upon high pressure being applied, this air is squeezed 70 from between the particles and the contiguous molecules compressed into close union which they retain, after removal of the pressure, by virtue of their own molecular cohesion. 75

It is found that when lampblack, in cake form in which the particles are bound together by their own molecular cohesion, is compounded with rubber, there is no dispersion of the lampblack throughout the atmosphere, for as soon as the cake is broken into lumps, the lumps are imbedded by the mill rolls in the rubber batch, which later surrounds the smaller particles and powder into which the lumps are subsequently reduced, and positively prevents the escape of 80 the lampblack. 85

While the invention is especially applicable to the treatment of lamp black it is obvious that it could be advantageously extended to the treatment of other finely divided carbon such as carbon black and the like. 90

Having thus described my invention, what 95 I claim and desire to protect by Letters Patent is:

1. A process for transforming finely divided carbon from a light, fluffy, powder condition to a solid block which comprises, 100 subjecting the carbon as such being treated upon all sides to a high pressure, while simultaneously venting the mass to permit the pressure to force the air therefrom through the vent until cohesion is produced between the particles and a permanent block formed. 105

2. A process for transforming finely

divided carbon from a light, fluffy, powder condition to a solid block which comprises, enclosing the carbon as such being treated in an envelope, of a material adapted to
5 permit the escape of air when the mass is confined and subjecting the enclosed mass under confinement to a high pressure, while simultaneously venting the mass to permit

the pressure to force the air therefrom through the vent until cohesion is produced 10 between the particles and a permanent block formed.

Signed at Detroit, Mich., this 27th day of October 1916.

WILLIAM W. McMAHAN.
